Primary Examiner — Doris Clark(74) *Attorney, Agent, or Firm* — Porter, Wright, Morris & Arthur, LLP(57) **CLAIM**

The ornamental design for a door-lock security device, as shown and described.

DESCRIPTION

FIG. 1 is a front perspective view of a door-lock security device in a closed configuration according to my new design;

FIG. 2 is a rear perspective view thereof;

FIG. 3 is a front view thereof;

FIG. 4 is a rear view thereof;

FIG. 5 is a right-side view thereof (the left-side view being a mirror image thereof);

FIG. 6 is a top view thereof;

FIG. 7 is a bottom view thereof;

FIG. 8 is a front perspective view of the door-lock security device in an open configuration according to my new design;

FIG. 9 is a rear perspective view thereof;

FIG. 10 is a front view thereof;

FIG. 11 is a rear view thereof;

FIG. 12 is a right-side view thereof (the left-side view being a mirror image thereof);

FIG. 13 is a top view thereof; and,

FIG. 14 is a bottom view thereof.
